UNITED STATES PATENT OFFICE.

CLAUDE H. WILLIS, OF MOBILE, ALABAMA.

CASE FOR CARDS.

SPECIFICATION forming part of Letters Patent No. 684,659, dated October 15, 1901.

Application filed June 4, 1901. Serial No. 63,145. (No model.)

To all whom it may concern:

Be it known that I, CLAUDE H. WILLIS, a citizen of the United States, residing at Mobile, in the county of Mobile and State of Alabama, have invented new and useful Improvements in Cases for Cards, of which the following is a specification.

This invention relates to cases for cards, and is especially designed for use in retaining the identification-cards required to be carried by all members of the well-known order of Elks and other benevolent and similar associations.

The object of the invention is to provide a light and durable metallic case which may be secured on the person of the wearer, so as to be at all times in his possession, and provided with novel means for securely holding the card in place, that may be securely and tightly closed to protect the card, that may be quickly opened to display the card, and which will be attractive and ornamental in appearance.

To these ends my invention consists in the features and in the construction, combination, and arrangement of parts hereinafter described, and particularly pointed out in the claims following the description, reference being had to the accompanying drawings, forming a part of this specification, wherein—

30 Figure 1 is a perspective view of my improved case, the same being shown partly open. Fig. 2 is a face view of the blanks from which the two sections of the case are made. Fig. 3 is a transverse section of the completed case.

Like reference-numerals indicate like parts in the several different views.

My improved case is made up of two sections 1 and 2, hinged together along their adjacent edges, as shown, each section being made in a single piece from sheet metal and approximately rectangular in shape. To form the connecting-hinge, each section is stamped up with a plurality of tongues 3 3, which are folded or curved over upon themselves to form eyes through which a pintle or hinge-pin 4 passes, as usual. The tongues 3 on one section are of course located opposite the spaces between the tongues on the adjacent section; and on the end tongues 3 of one or the other of the two sections are formed lat-

erally-projecting lips 5, which are adapted to be bent over to engage the ends of the pintle or hinge-pin 4 and prevent endwise displacement of the latter or accidental separation or detachment of the two sections. The blank from which each of the sections 1 and 2 is made is bent inwardly at right angles along its opposite ends and along the edge which lies opposite the hinge to form flanges 6 and 7, said flanges being united at the outer corners of each of the sections by a diagonal flange 9, as most clearly shown in Fig. 2 of the drawings. Each of the two blanks at the said outer corners is formed with triangular wings 8 8, which are formed integral with the diagonal flanges 9 and are folded down parallel with the body of the case along the lines 10, said wings at their edges resting between the flanges 6 7 and their surfaces lying flush with the edges of said flanges. The blank from which one of the sections—as section 1, for example—is made is also formed centrally at its outer edge with a tongue which is bent or curved up into tubular shape to form a fastening device or clasp 12 to hold the two sections closed. When the two sections are closed one upon the other, the clasp 12 will spring or snap over the edge of the adjacent section and hold the two sections locked in a manifest manner. At one end of one of the blanks—as 2, for example—is provided an integral tongue 13, having two slots or apertures 14 14 therein, the said tongue being folded back upon itself along the line 15, so that the slots or apertures will register with one another. By bending or folding the tongue in the manner described the same is made of double thickness, and hence of increased strength and capable of withstanding greater wear, said tongue forming a convenient means for suspending the case from or attaching it to the person of the wearer. Within the flanges 6 and 7 of the two sections 1 and 2 of the completed case the identification or other card is fitted, the corners of said card being inserted beneath the corner-flaps formed by the wings 8 and held in place by said wings. When the card has been inserted and the case is closed up, the flanges 6 7 and the flanges of one section will close against or abut the corresponding parts of the other sec-

tion, thus forming a tight case which securely incloses the card and effectually protects the same. In practice the end of a watch-chain, key ring or chain, or the like is 5 passed through the slots in the tongue 13, thus securely attaching the case to the wearer.

The surface of the case can be suitably ornamented and in practice have embossed or otherwise suitably designated thereon the 10 symbols of the order to which the identification-card relates.

Having described my invention, what I claim is—

1. A card-case comprising two substantially rectangular sections hinged together at their inner adjacent edges, each of said sections being formed from a single metallic blank bent up along its ends and outer edge to form flanges and provided at its outer corners with triangular wings bent over between 15 20

said flanges to form retaining-flaps, substantially as described.

2. A card-case comprising two substantially rectangular sections hinged together at their inner adjacent edges, each of said sections being formed from a single sheet-metal blank, and one of said sections being provided with a projecting tongue provided with two apertures, said tongue being bent or folded upon itself to form a double thickness, the 25 30 35 two apertures registering with one another to form a suspending or attaching means, substantially as described.

In testimony whereof I have hereunto set my hand in presence of two subscribing witnesses.

CLAUDE H. WILLIS.
